STEPHEN D. HARTOG, OF ST. LOUIS, MISSOURI, ASSIGNEE, BY MESNE ASSIGNMENTS, TO INLAND MACHINE WORKS, OF ST. LOUIS, MISSOURI, A CORPORATION OF MISSOURI.

PISTON-RING.

1,386,707.

Specification of Letters Patent. Patented Aug. 9, 1921.

Application filed January 24, 1919. Serial No. 272,830.

To all whom it may concern:

Be it known that I, STEPHEN D. HARTOG, a citizen of the United States, residing at the city of St. Louis and State of Missouri, have invented a new and useful Piston-Ring, of which the following is a specification.

This invention relates to piston rings.

An object of the invention is to provide an improved piston ring having overlapping ends which, when the ring is mounted within the groove of a piston and within a cylinder, are retained close together by the side walls of the groove in which the ring is mounted and which are caused by the resiliency of the metal to press laterally against the side walls of the groove in the piston and thus form a close seal to prevent the passage of gas while the resiliency of the metal is also utilized to expand the ring in contact with the cylinder wall.

Another object of the invention is to provide a ring possessing the above characteristics and also constructed so that the strains are equalized or apportioned throughout the circumference of the ring, thus preventing excessive strain upon any portion of the ring when the ring is under compression on a piston and within a cylinder.

Other objects will appear from the following description in which reference is made to the drawing illustrating one embodiment of my improved piston ring, and in which—

Figure 1 is a perspective view of the ring.

Fig. 2 is an elevation looking toward one of the side edges of the ring.

Fig. 3 is an elevation looking toward the periphery of the ring.

Fig. 4 is an enlarged sectional view on the line 4—4 of Fig. 2.

Fig. 5 is an enlarged sectional view on the line 5—5 of Fig. 2, showing the spaced overlapping ends.

My improved ring is composed of a single piece of metal split for a portion of its circumference to form two overlapping ends 1 which are separated from each other by a space 2 which is made by the implement or tool employed to split the ring. In its expanded form the ends of the ring are separated from the adjacent shoulders on the ring by spaces 3 which permit the ring to be compressed within a cylinder in which the ring is intended to operate. As shown

the combined width of the overlapping ends 55 1 plus the width of the two is greater than the width of the remaining portion of the ring; but when the ring is compressed within a cylinder of the size in which the ring is intended to operate and within the groove 60 of a piston, the overlapping ends 1 of the ring are pressed close to each other so that the combined width of the overlapping ends when they are bearing against each other is equal to the width of the remaining portion 65 of the ring. It will be observed that the resiliency of the metal is utilized in order to cause the overlapping ends 1 of the ring to press laterally against the side walls of the groove in the piston without interfering 70 with the freedom of expansion and contraction of the ring during operation of the piston. The pressure of the overlapping ends 1 against the side walls of the groove forms a close seal to prevent passage of gas between the ends of the ring and the side walls 75 of the groove, while at the same time the overlapping ends are so close together that no material quantity of the gas can pass through either of the spaces 3 and the 80 space 2.

A groove 4 is formed in the inner side of that portion of the ring opposite the overlapping ends 1. The groove 4 may be of any desired length and should be of a depth 85 sufficient to permit the portion of the ring in which it is formed to yield or twist without undue resistance when the ends 1 are pressed together in the groove of the piston, and to prevent excessive strains upon 90 the ends 1 in their movement toward and away from each other and to apportion or equalize the strains throughout the circumference of the ring. Thus during the reciprocation of the piston the ring is permitted to operate freely to maintain approximately uniform pressure against the cylinder wall throughout the circumference of the ring, and also to press laterally against the side walls of the groove. 100

A ring of the above-described character may be manufactured economically and is more efficient than rings of usual construction for the reason that a close joint is formed by the ring with the cylinder wall, 105 and also with the walls of the groove in the piston in which the ring is mounted.

I do not restrict myself to unimportant

and unessential features of construction, but what I claim and desire to secure by Letters Patent, is:—

1. A piston ring, comprising a solid portion which is substantially equal in width to the width of the piston groove in which the ring is to operate, and overlapping ends integral with the solid portion extending a substantial portion of the circumference of the ring and being spaced apart throughout their length, said ends having a combined width equal to the width of the solid portion of the ring and being arranged to press laterally against the side walls of the piston groove; said ring having a groove in the inner side of the solid portion opposite from the overlapping ends, said groove being of

less length than the length of the solid portion of the ring.

2. A piston ring, comprising a solid portion which is substantially equal in width to the width of the piston groove in which the ring is to operate, and overlapping ends integral with the solid portion extending a substantial portion of the circumference of the ring and being spaced apart throughout their length, the spaced overlapping ends integral with the solid portion of the ring having a combined width equal to the width of the solid portion of the ring; said solid portion having a groove in the inner side thereof of less length than the solid portion of the ring.

STEPHEN D. HARTOG.
